(57) **CLAIM**

The ornamental design for a fixing hardware for roof panel,
as shown and described.

DESCRIPTION

FIG. 1 is a top, perspective view of the fixing hardware for
roof panel, showing my new design;

FIG. 2 is a front view of the fixing hardware for roof panel
of FIG. 1;

FIG. 3 is a rear view of the fixing hardware for roof panel
of FIG. 1;

FIG. 4 is a first side view of the fixing hardware for roof
panel of FIG. 1;

FIG. 5 is a second side view of the fixing hardware for roof
panel of FIG. 1;

FIG. 6 is a top view of the fixing hardware for roof panel of
FIG. 1;

FIG. 7 is a bottom view of the fixing hardware for roof panel
of FIG. 1;

FIG. 8 is a cross-sectional view taken in the direction of the
line 8-8 of FIG. 2;

FIG. 9 is a cross-sectional view taken in the direction of the
line 9-9 of FIG. 6;

FIG. 10 is a cross-sectional view taken in the direction of the
line 10-10 of FIG. 6;

FIG. 11 is a cross-sectional view taken in the direction of the
line 11-11 of FIG. 6;

FIG. 12 is an enlarged view of area 12 circumscribed within
FIG. 8, thereof;

FIG. 13 is an enlarged view of area 13 circumscribed within
FIG. 6, thereof;

FIG. 14 is an enlarged view of area 14 circumscribed within
FIG. 9, thereof; and,

FIG. 15 is an enlarged view of area 15 circumscribed within
FIG. 10, thereof.

The dash-dash broken lines illustrate portions of the fixing
hardware for roof panel. The dot-dot-dash broken lines
illustrate the boundaries of the enlarged views and the view
indicators. The long dash-short dash broken lines illustrate
